(57) **CLAIM**

The ornamental design for a false eyelash, as shown and described.

DESCRIPTION

FIG. 1 shows a perspective view of a false eyelash; FIG. 2 shows a front elevation view of the false eyelash of FIG. 1;

FIG. 3 shows a rear elevational view of the false eyelash of FIG. 1;

FIG. 4 shows a perspective view of a false eyelash; FIG. 5 shows a front elevation view of the false eyelash of FIG. 4;

FIG. 6 shows a rear elevational view of the false eyelash of FIG. 4;

FIG. 7 shows a perspective view of a false eyelash; FIG. 8 shows a front elevation view of the false eyelash of FIG. 7; and,

FIG. 9 shows a rear elevational view of the false eyelash of FIG. 7.
The broken lines are shown for the purpose of illustrating parts of the false eyelash that form no part of the claimed design.
